UNITED STATES PATENT OFFICE

GEORGE P. FARMER, OF BROOKLYN, N. Y., AND JACOB J. HATCHER, OF PHILADELPHIA, PA., ASSIGNORS TO E. C. PRATT, BROTHER & CO.

DESIGN FOR CARD OF BUTTONS.

Specification forming part of Design No. 7,914, dated December 8, 1874; application filed September 30, 1874.
[Term of Patent 14 years.]

To all whom it may concern:

Be it known that we, **GEORGE P. FARMER**, of Brooklyn, New York, and **J. J. HATCHER**, of Philadelphia, Pennsylvania, have invented a Design for Card of Buttons, of which the following is a specification:

The face of the card, part only of which is represented in the accompanying drawing, is separated by narrow bands, which cross each other, into oblong spaces, A, there being two spaces in the width of the card, by preference, six in the length.

Each space is covered with foil, on which twelve pearl buttons are arranged, in the manner shown in the drawing, the said buttons being stitched to the card.

The bands between the spaces are ornamented, substantially as shown in the drawing, so as to impart a pleasing effect to the card.

Irrespective of any specific colors of card, foil, or printed ornaments,

We claim—

The design for a card of buttons, substantially as described, and illustrated in and by the accompanying drawing.

In testimony whereof we have signed our names to this specification in the presence of two subscribing witnesses.

GEORGE P. FARMER.
JACOB J. HATCHER.
